A. N. GARLAND, OF WEST CHARLESTON, VERMONT.

Letters Patent No. 71,733, dated December 3, 1867.

IMPROVED DRESS FOR MILLSTONES.

The Schedule referred to in these Letters Patent and making part of the same.

TO ALL WHOM IT MAY CONCERN:

Be it known that I, A. N. GARLAND, of West Charleston, in the county of Orleans, and State of Vermont, have invented a new and improved Millstone Dress; and I do hereby declare the following to be a full, clear, and exact description of the same, reference being had to the accompanying drawings, forming part of this specification, and in which—

Figure 1 is a view of the face of one of the stones.

Figures 2 and 4 are vertical sections through the centre of the stones as they are in position for working.

Figure 3 is a longitudinal section of the pattern used in bosoming the stone.

Similar letters of reference indicate corresponding parts in the several figures.

In this invention the furrows are made wide, shallow, and smooth, one edge being cut clean and sharp. Between the furrows the surface near the centre of the stone is smooth, and at other parts of the stone is cut like the face of a file. A new method of bosoming the stone is also used.

In order that others skilled in the art to which my invention appertains may be enabled to make and use the same, I will proceed to describe it in detail.

In the drawings, A represents the upper and B the lower stone. The channels C C are curved, radiating from the centre, and arranged in the turbine or vertical manner, having their bottom inclined from the side c c to the deeper side c' c', where they terminate at the bottom of a perpendicular wall, the upper edge of which is carefully dressed and smoothed into a sharp, clear cutting-edge. At the inner end of the channels C C the incline commences at the top of the perpendicular wall c', terminating at the bottom of the next one to the right of it, thus occupying the whole space between the walls c' c'. At the outer end of the channels their inclined surface does not occupy the whole distance from c' to c', but only the distance from c to c' on its right, or about one-half the distance from c' to c'. The surface of stone between the point c' and the point c on its right hand, and extending from the outer edge of the stone to the line D, is flat, and cut in fine threads, like the face of a file, the threads running in the same direction as the channels C C. Inside of the line D the surface of stone between the channels is perfectly smooth. The surface enclosed by the circular line D is designed to be in proportion to the whole surface of the stone nearly as shown in the drawing, in which the diameter of the circle D is about two-fifths the diameter of the whole stone. The depth of the channels C C is one-eighth of an inch in the bed-stone, and three-sixteenths of an inch in the upper stone. The inclined bottom surface of the channels is made perfectly smooth. There is no difference between the channels in the upper and those in the nether stone, except in their depth. To bosom the upper stone, I make a pattern, of which a longitudinal section is shown in fig. 3, the length of which, from E to F, is to be one-half the radius of the stone, and the depth at G, the deepest part, about one-sixteenth of an inch, running to nothing at F. H is the rod on which it turns, standing vertically in the centre of the eye. I paint the under side of the pattern from E to F, then, while the paint is not dry, apply it to the stone and rotate it till the paint, where it touches, adheres to the surface of the stone. I then remove the pattern and pick off the painted surface of the stone, continuing the operation till the bosom is formed as desired. This part of the stone is then to be smoothed as perfectly as possible, as is also the corresponding surface of the bed-stone.

The old form of channel is cut so as to occupy about one-third of the surface from c to c', and is one-quarter of an inch or more in depth. Such a narrow and deep furrow causes a great amount of friction, and the meal leaves the stone heated, especially in grinding fast. The perpendicular walls c' c', with smooth, sharp, upper edges, prevent the bran from being chopped up, and render the separation of the bran from the flour more perfect. Millers are very liable to break off small particles from the edge of the shoulder or wall c' c', leaving it rough and irregular, imagining that such irregularities can do no harm. The effect, however, is that the crushed wheat passes over this shoulder, and the bran adhering to it, catches on the sharp points along the rough edge, and is cut and ground fine, so that it cannot be separated from the flour. In my invention these defects in the working of the millstones are completely obviated. The flour runs freely in the smooth, well-defined channels, the air is admitted without obstruction in the deeper channels of the upper stone, the sharp upper edges of the walls c' c' refuse to tear and grind the bran and the smooth inner surface of stone,

inside of the line D, cracks and crushes instead of cutting the kernel, while the threaded file-surface on the outer part of the stone thoroughly pulverizes the flour.

Having thus described my invention, what I claim as new, and desire to secure by Letters Patent, is—

The millstone dress above described, consisting of the smooth surface inside, and the file surface outside of the line D, together with the smooth shallow channels in the bed-stone, and deeper ones in the runner, the channels in both stones being constructed in the curved form above described, widening towards the rim of the stones, and having one smooth inclined surface and one perpendicular wall, c', the upper edge of the wall being sharp and smooth, and all the parts being constructed and arranged substantially in the manner and for the purposes specified.
